This technical drawing illustrates a vertical structure, possibly a wall or a series of panels, with various angles and features labeled. The top edge of the structure is marked with an angle of 21°. Below this, a horizontal line is labeled with 16° and 25°. The right side of the structure is labeled with 23° and 22°. The bottom edge is labeled with 25° and 25°. The bottom right corner contains the text "Inventor" and "George B. McGlade".

LOOSE LEAF BINDING

George B. McGlade, Long Island City, N. Y., assignor to Acco Products, Inc., a corporation of New York

Application June 19, 1936, Serial No. 86,027

17 Claims. (Cl. 129—1)

The invention relates broadly to improvements in a loose leaf binder and more particularly to means to selectively adapt it to any of a plurality of different capacities.

- 5 An object of the invention is to provide a loose leaf binder having reinforced backing means with associated means to reduce the width of said backing means to adapt the binder to sheaves of papers of various thicknesses.
- 10 Another object is to provide one binder cover with attached backing means and means easily operable to adjust the binder to suit a sheaf of predetermined thickness before securing said backing means to the other binder cover.

- 15 Another object is to provide efficient inexpensive means to stiffen the back of a loose leaf binder.

The foregoing and such other objects of the invention as will appear hereinafter as the description proceeds will be more readily understood from a perusal of the following specification, reference being had to the accompanying drawing, in which:

Fig. 1 is a perspective view of the binder embodying the invention, showing a sheaf of papers, partly broken away, bound therein.

Fig. 2 is a fragmentary end elevational view of the bound sheaf.

Fig. 3 is a perspective view of the novel backing means.

Fig. 4 is a fragmentary perspective view similar to Fig. 3, of a modified construction.

When records are kept on loose papers such as for example, letter copies or the like, preservation of the papers is frequently desirable. For this purpose a sheaf of such loose papers as shown at 11 may be securely bound together between the binder covers 12 and 13. Inasmuch as the bound sheaf of papers usually is stored for occasional reference only, it is desirable that the binder covers 12 and 13 and such means as are employed for securing the papers between said covers, such as a prong fastener 14, should be of the most inexpensive construction. The rigidity of the bound sheaf of papers and the convenience with which it may be withdrawn from between a number of similarly bound sheaves are greatly improved if the binder is provided with a back means such as shown at 15. The provision of suitable backing means also affords a place for indicating the nature of the contents of the sheaf enabling examination without handling the binder. Additional rigidity is afforded the binder by providing a suitable reinforcing or stiffening section 16 in the backing means 15 and because

of the varying uses the binder is put to, it is essential that the backing means be easily changed in width.

As shown in Figs. 1 and 2, the binder covers 12 and 13 preferably are flat cloth covered members each having a hingedly connected binding flap 17 on one edge formed with suitably spaced openings 18 for receiving the prongs 14a of fastener 14. It is obvious that the papers 11, which also are perforated to receive prongs 14a are securely bound by the fastener 14 to and between binding flaps 17 in a manner to permit ready opening and closing of the covers 12 and 13 along their respective flap forming hinge members 19.

The backing means 15, as best shown in Fig. 3, preferably includes a substantially rectangular flexible strip 21 having an adhesive coating 22 on one face. The reinforcing or stiffening section 16 preferably consists of a substantially rectangular stiff section, such as a heavy cardboard, having a plurality of spaced apart parallel scores 23 extending longitudinally on one face preferably adjacent one edge only. The unscored portion 24 of said stiff section is secured by the adhesive to flexible strip 21 as shown.

In assembling, the sheaf of papers is first bound between the covers and then one margin 21a of the flexible strip 21 is glued to the margin of one of the covers and the strip is then carried across the back edge of the sheaf. The required number of severable portions 25 of the stiff section 16, defined by scores 23, is then removed to reduce the stiff section to the desired width. The other marginal edge 21b of the flexible strip is then glued over the margin of the other cover 13 with the scored face of section 16 disposed toward the back edge of the sheaf. Any severable portions remaining are glued to the flexible strip to increase the rigidity of the back.

The structure shown in Fig. 4 is substantially like that illustrated in Fig. 3 except that the severable portions 25a, defined by scores 23a, are arranged adjacent each longitudinal edge of stiff section 16a, thus permitting removal of portions from one or both longitudinal edges of said section.

The structure described also has the advantage of being easily adapted for re-use on sheaves of the same or smaller thicknesses. To apply a previously used binder to a sheaf which is smaller than the sheaf originally contained therein, the margin 21b of the flexible strip is separated from the cover 13 and one or more severable portions 25 of the stiff section are removed. The margin

21b then is trimmed to the desired width and re-glued to the cover.

The structures described obviously provide inexpensive rigid backing means for a bound sheaf 5 of papers and it is not desired to limit the invention to the precise details disclosed but to embrace such structures as fall within the spirit of the invention and the scope of the appended claims.

10 I claim:

1. In a loose leaf binder, covers adapted to be disposed on opposite faces of a sheaf of papers, a flexible strip adapted to extend over an edge of said sheaf, said strip having its longitudinal margins secured to complementary edges of the covers, a stiff section secured to said strip between said margins, said section including a plurality of severable portions.

2. In a loose leaf binder, covers adapted to be disposed on opposite faces of a sheaf of papers, a flexible strip adapted to extend over an edge of said sheaf, said strip having its longitudinal margins secured to complementary edges of the covers, a stiff section disposed between said covers 15 and secured to said strip, and a plurality of parallel scores formed in said section defining severable portions.

3. In a loose leaf binder, covers adapted to be disposed on opposite faces of a sheaf of papers, a flexible strip adapted to extend over an edge of said sheaf, said strip having its longitudinal margins secured to complementary edges of said covers, a stiff section having one face secured to the inside face of said strip, and a plurality of 30 parallel scores formed in the exposed face of said section defining severable portions.

4. In a loose leaf binder, covers adapted to be disposed on opposite faces of a sheaf of papers, a flexible strip adapted to extend over an edge of 40 said sheaf, the longitudinal margins of said strip being glued to complementary edges of the covers, a stiff section glued to said strip, and a plurality of parallel longitudinal scores formed in one face of said section defining a plurality of 45 severable portions.

5. In a loose leaf binder, covers adapted to be disposed on opposite faces of a sheaf of papers, a flexible strip adapted to extend over an edge of said sheaf, said strip having its longitudinal margins glued to complementary edges of the covers, a stiff section having one face glued to the inside 50 face of said strip between said margins, and a plurality of parallel longitudinal scores formed in the exposed face of said section defining a plurality of 55 severable portions.

6. In a loose leaf binder, covers adapted to be disposed on opposite faces of a sheaf of papers, a flexible strip, adapted to extend over an edge of said sheaf, having its longitudinal margins secured to complementary edges of the covers, a stiff section having one face secured between said 60 margins to said strip, and a plurality of parallel longitudinal scores formed in said section, said scores being adjacent one edge only.

7. Means adapted to secure the covers of a loose leaf binder together, said covers being adapted to overlie opposite sides of a sheaf of papers, comprising in combination, a flexible strip adapted to extend across an edge of said sheaf and have its longitudinal margins secured one to each cover, a stiff section having one face secured between said margins to the inside face of said strip, and a plurality of parallel scores formed in the exposed face of said stiff section defining severable portions.

8. Means adapted to secure the covers of a loose

leaf binder together, said covers being adapted to overlie opposite sides of a sheaf of papers, comprising in combination, a flexible strip adapted to extend across an edge of said sheaf and have its longitudinal margins secured one to each cover, a stiff section having one face secured between said margins to the inside face of said strip, and a plurality of parallel scores formed in the exposed face of said stiff section defining severable portions.

9. Means adapted to secure the covers of a loose leaf binder together, said covers being adapted to overlie opposite sides of a sheaf of papers, comprising in combination, a flexible strip adapted to extend across an edge of said sheaf and have its longitudinal margins secured one to each cover, a stiff section secured between said margins to the inside face of said strip, and a plurality of severable portions formed in said stiff section.

10. Means adapted to secure the covers of a loose leaf binder together, said covers being adapted to overlie opposite sides of a sheaf of papers, comprising in combination, a flexible strip adapted to extend across one edge of said sheaf and have its longitudinal margins secured one to each cover, a stiff section secured between said margins to said strip, and a plurality of severable portions adjacent only one longitudinal edge of said stiff section.

11. Means, comprising in combination, a substantially rectangular flexible strip having an adhesive on one face, a substantially rectangular stiff section secured by said adhesive to said strip, said stiff section being spaced substantially midway between the longitudinal edges of said flexible strip, and parallel longitudinal scores formed in said stiff section defining severable portions.

12. Means, comprising in combination, a substantially rectangular flexible strip having an adhesive on one face, a substantially rectangular stiff section secured by said adhesive to said strip, said stiff section lying substantially midway between the longitudinal edges of said flexible strip, and parallel scores formed in said stiff section defining severable portions.

13. Means, comprising in combination, a flexible strip, a stiff section substantially narrower than said flexible strip, severable portions forming a part of said stiff section, said flexible strip being secured to the non-severable portion of the stiff section.

14. Means, comprising in combination, a substantially rectangular flexible strip, a substantially rectangular stiff section partially secured to said flexible strip, said stiff section being substantially narrower than said flexible strip, and a plurality of spaced longitudinal scores formed in said stiff section defining severable portions, said portions normally being detached from said flexible strip.

15. Means, comprising in combination, a substantially rectangular flexible strip having an adhesive on one face, a substantially rectangular stiff section having one face partially secured by said adhesive to said strip, said stiff section being substantially narrower than said flexible strip, and a plurality of spaced longitudinal scores formed in said stiff section defining severable portions, said portions being adapted to be secured to said strip by said adhesive if not severed.

16. Means, comprising in combination, covers adapted to be disposed on opposite faces of a sheaf of papers, a flexible strip adapted to extend

across an edge of said sheaf, said strip being gummed on one face and having its longitudinal margins secured to the complementary edges of the covers, a stiff section having one face secured between said covers to the inside face of said strip, and a plurality of parallel longitudinal scores adjacent only one edge of said section, said scores being formed on the face disposed toward the edge of said sheaf.

adapted to overlie opposite sides of a sheaf of papers, comprising in combination, a flexible strip adapted to extend across an edge of the sheaf and have its longitudinal margins secured to the complementary edges of the covers, a stiff section secured between said margins to the inside face of said strip, and a plurality of severable portions arranged adjacent each longitudinal edge of said section. 5

GEORGE B. McGLADE. 10

17. Means adapted to secure the covers of a loose leaf binder together, said covers being
